Primary Examiner — Terry Wallace(74) Attorney, Agent, or Firm — Merchant & Gould P.C.(57) CLAIM

The ornamental design for the combination napkin and utensil holder, as shown and described.

DESCRIPTION

FIG. 1 is a front view of a combination napkin and utensil holder showing my new design; and,

FIG. 2 is a top view thereof.

The undisclosed bottom and rear views are not being claimed. The broken line showing of the sides of the combination napkin and utensil holder forms no part of the claimed design.
